CLAIM

The ornamental design for a dental pick, as shown and described.

DESCRIPTION

FIG. 1 is a front elevational view of a dental pick showing my new design;

FIG. 2 is a top plan view thereof;

FIG. 3 is a right end view thereof; and,

FIG. 4 is a left end view thereof.

The rear elevational view comprises a mirror image of the front elevational view and the bottom view is substantially identical to the top plan view. The ribs illustrated in dashed lines do not form part of the claimed design.
